UNITED STATES PATENT OFFICE

ALVIN N. GUSTAVSON, OF JAMESTOWN, NEW YORK, ASSIGNOR TO AUTOMATIC REGISTERING MACHINE COMPANY, INC., A CORPORATION OF NEW YORK

VOTING MACHINE

Application filed October 28, 1936. Serial No. 144,870.

This invention relates to an improvement in voting machines, and more particularly in voting machines of the type in which votes are cast by the operation of pointers, and in 5 means for preventing the operation of certain pointers.

A portion of the keyboard of a voting machine is customarily reserved to permit the voter to indicate his preference with reference to certain amendments or questions, 10 which are presented for his determination.

The space below a pair of pointers, one for "Yes" and the other for "No", is intended to receive the question or amendment to be voted upon. It has often been found that the questions or amendments are so long that they extend beyond this space so that, instead of occupying simply the space below one pair of pointers the question occupies the space 20 below several pairs of pointers. It is desirable that only one pair be actuated, and while it is possible to lock the other pairs by concealed mechanism, it has been found that voters have failed to indicate their preference 25 because there was nothing on the keyboard to indicate which pair of pointers should be actuated.

The primary object of this invention is to avoid this difficulty by providing means 30 which not only prevent the operation of certain pointers, but which cover them so that the voter can readily understand which pair of pointers is to be actuated.

Other objects of this invention will appear 35 from a consideration of the following description taken in connection with the drawings which form a part thereof, and in which

Fig. 1 is a front elevation of a keyboard 40 of a voting machine on which is shown a question which extends below three pairs of pointers;

Fig. 2 is a front elevation and Fig. 3 is a rear elevation of a lockout embodying this invention; and

Fig. 4 is a sectional view, illustrating the 45 relationship of this lockout to the pointers on the keyboard.

In the drawings, the keyboard 10 is shown 50 provided with a plurality of pointers 11-11, 12-12, and 13-13, which are used in pairs,

one to be depressed to vote "Yes", and the other to be depressed to vote "No." Below the pointers is fixed on the keyboard a flanged, horizontal channel plate 14, within which is placed a card, 15, on which the question to be 55 answered by the voter is printed. In the present instance, as shown in Figure 1, the question on the card 15 is of such length that it extends below the pointers 11-11, 12-12 and 13-13.

Obviously when a question extends below a plurality of pointers the particular pair of pointers to be depressed in voting upon this question must be clearly indicated, so that the voter can, without difficulty or loss of time, 65 register his preference. Thus, in the present instance, it has been desired to use the pair of pointers 12 to vote on the question.

In order to prevent the voter from using the pair of pointers 11-11 or the pair of 70 pointers 13-13, a lockout 16 is provided. This lockout is preferably of sheet metal having a front face 17, the lower edge of which is bent to provide a rectangular horizontal channel 18, opening inwardly, one end of 75 which is cut away to provide a rectangular notch 19. At the back of the lockout 16 are provided a plurality of tongues 20, parallel to and spaced from the front face 17. The pointers 11, 12 and 13 each include an arm 21, 80 which is spaced from the face of the keyboard 10, and a button 22 at the end of said arm.

The lockout 16 is installed by inserting the tongues 20 behind the arms 21 of the selected pointers, and snapping the channel 18 over 85 the buttons 22. The notch 19 permits the installation of the lockout 16 without interfering in any way with the actuation of the pointer next to the left. The pointers are thus concealed, and cannot be actuated. 90 Moreover, the lockouts not only conceal the pointers which are not to be used, but they bring the pointers 12, which are to be used, into prominence so that the voter can at a glance see how he is to indicate his preference 95 with reference to the question submitted for his decision.

As shown in Figures 2 and 3, each lockout is intended to cover one pair of pointers. It is obvious, however, that the lockouts could 100

be extended in length indefinitely so that, instead of covering simply one pair they could cover any number of pointers.

While the lockout 16 is shown and described as applied to question pointers, it is obvious that they could be applied as well to any pointers on the keyboard. The showing and description of one embodiment only is not to be considered as a limitation thereto, since other embodiments could be made without departing from the spirit and scope of the invention, as set forth in the following claims.

Having thus set forth my invention, what I claim as new and for which I desire protection by Letters Patent is:

1. In a voting machine having a keyboard, and a plurality of pointers mounted on said keyboard for pivotal movement thereover, said pointers each including an arm spaced from said keyboard, a lockout, comprising a plate having tongues, which tongues are adapted to be inserted in the spaces between the keyboard and the arms of certain predetermined pointers, the plate being in front of said pointers when in position, thereby preventing the operation thereof.

2. In a voting machine having a keyboard, and a plurality of pointers mounted on said keyboard for pivotal movement thereover, said pointers each including an arm spaced from said keyboard, a lockout, comprising a plate having tongues, which tongues are adapted to be inserted in the spaces between the keyboard and the arms of certain predetermined pointers, the plate when in position being in front of and covering said pointers.

3. In a voting machine having a keyboard, and a plurality of pointers mounted on said keyboard for pivotal movement thereover, said pointers each including an arm spaced from said keyboard and a button projecting outwardly from said arm, a lockout comprising a plate having tongues and a rectangular inwardly opening channel, said tongues being adapted to be inserted in the spaces between said keyboard and the arms of certain predetermined pointers, and said channel receiving and concealing the buttons of said pointers when in position, thereby preventing the operation thereof.

4. A lockout for pointers of a voting machine comprising a plate having a face portion, a horizontal inwardly facing channel at the lower edge of said face portion, said channel being adapted to enclose said pointers and prevent actuation thereof, and means for fixing said lockout upon said pointers.

5. A lockout for pointers of a voting machine comprising a plate having a face portion, a horizontal inwardly facing channel at the lower edge of said face portion, said channel being adapted to enclose said pointers and prevent actuation thereof, tongues behind and spaced from the face portion of said

plate for fixing said lockout upon said pointers.

6. A lockout for pointers of a voting machine comprising a plate having a face portion, a horizontal inwardly facing channel at the lower edge of said face portion, said channel being adapted to enclose said pointers and prevent actuation thereof, tongues behind and spaced from the face portion of said plate for fixing said lockout upon said pointers, and a notch in said face portion at one end of said channel, which permits the installation of said plate without interfering with the operation of any pointer other than those on which said plate is fixed.

In testimony whereof I have affixed my signature.

ALVIN N. GUSTAVSON.
